MACHINE FOR THE EXTRACTION OF GOLD
AND OTHER MINERALSSterling Stageberg, Minneapolis, Minn., assignor
to Wesley Styles, Minneapolis, Minn.

Application September 28, 1940, Serial No. 358,763

11 Claims. (Cl. 209—200)

My invention relates to machines for the extraction of gold from gold bearing ore, and has for an object to produce a machine by means of which gold flour may be readily removed from the ore.

Another object of the invention resides in providing a machine in which flour in the form of flake-like particles having a great superficial area may be readily removed from the ore.

A still further object of the invention resides in providing a machine in which a great percentage of the gold may be removed from the ore.

Another object of the invention resides in providing a machine utilizing a quantity of mercury for the extraction of the gold and in providing pump means within the machine for the circulation of the ore, said pump means acting in conjunction with the mercury to produce suction and pressure within the machine.

A feature of the invention resides in constructing the machine with a drum containing the mercury and rotatable to maintain the mercury within the drum in the form of an annulus encircling the inner periphery of the drum.

An object of the invention resides in providing a rotor within the drum arranged eccentrically of the drum and adapted to dip into the mercury.

Another object of the invention resides in constructing the rotor with a plurality of fins extending about the circumference thereof and entering the mercury.

A still further object of the invention resides in providing a pump member movable with the rotor and having vanes extending into the mercury.

A still further object of the invention resides in constructing the rotor with threads upon the inner surface thereof serving to produce circulation of the mercury within the rotor.

Another object of the invention resides in the construction of the machine by means of which the ore is directed into the machine and the residue removed therefrom.

Other objects of the invention reside in the novel combination and arrangement of parts and in the details of construction hereinafter illustrated and/or described.

In the drawings:

Fig. 1 is a longitudinal elevational sectional view of a machine for the extraction of gold from gold bearing ore and illustrating an embodiment of my invention.

Fig. 2 is a cross sectional view taken on line 2—2 of Fig. 1.

Fig. 3 is a cross sectional view taken on line 3—3 of Fig. 1.

5 My invention comprises a rotor 10 mounted upon a horizontally extending shaft 11. The shaft 11 is rotatably mounted in two bearings 12 and 13 carried by two standards 14 and 15. The standards 14 and 15 are provided with feet 17 which are arranged to rest upon the surface on which the machine is supported and by means of which the machine may be bolted in place. The two standards 14 and 15 have tubular portions 18 and 19 which encircle the shaft 11 and are spaced therefrom to form annular passageways 21 and 22 therebetween. The bearing 13 is provided with a seal 23 by means of which leakage through the bearing 13 is prevented. A nipple 24, formed on the standard 14, has connected to it a pipe 25 by means of which the ore from which the gold is to be extracted may be fed into the machine. This nipple is constructed with a bore 26 which communicates with the passageway 21. The nipple 24 extends upwardly from the tubular portion 18 of the standard. In like manner the standard 15 is constructed with a nipple 27 which depends from the tubular portion 19 of said standard. This nipple has a bore 28 therein which communicates with the passageway 22. A pipe 29 connected to the nipple 27 conducts away the residue from the machine.

10 The rotor 10 is disposed within a drum 31 which has attached to the ends thereof two flanges 32 and 33. These flanges are bolted to the drum 31 by means of cap screws 34. The flanges 32 and 33 are provided with bearing portions 35 which are rotatably mounted upon two eccentric bushings 36 and 37. The eccentric bushings are provided with bores which receive the ends of 15 the tubular portions 18 and 19 of standards 14 and 15, previously referred to. These bushings are rigidly attached to the said tubular portions in any suitable manner. A seal 38 arranged in a recess 30 in each of the flanges 32 and 33 forms a fluid tight connection between the drum and the two bushings 36 and 37. The drum 31 is constructed with a bore 50 which is enlarged at one end as indicated at 39. The remainder of the bore 50 is formed with internal threads 41, the 20 purpose of which will be subsequently more fully described.

25 Within the enlarged portion 39 of the bore of drum 31 is arranged a pump mechanism 40 having a pump head 43, best shown in Fig. 3. This pump head may be of any suitable shape and has

two blades 44 and 45 extending outwardly therefrom. On the ends of the head 43 are provided end plates 46 and 47 of the same diameter as the diametral dimension of the head 43 taken across the blades 44 and 45. These plates and the head 43 are all bolted to the rotor 10 by means of cap screws 48 which extend through said parts and are threaded into said rotor. The plate 46 has two holes 51 and 52 in the same disposed in the same circumferential direction with reference to the blades 44 and 45 and in close proximity thereto. Likewise the plate 47 has two similar holes 53 and 54 on the opposite sides of the blades 44 and 45. Within the drum 31 is provided a quantity of mercury which, when the drum and rotor rotate, is thrown outwardly by centrifugal force to take the form of a hollow cylinder designated by the dash line 55 and having a cavity 56 within the same. The quantity of mercury is sufficient so that the edges of the two plates 46 and 47 are at all localities immersed in the mercury and also the tips of the blades 44 and 45. The holes 51, 52, 53 and 54 are so located that, when the holes are at the uppermost portion of the machine, said holes communicate with the cavity 56 and when said holes are at the lowermost portion of the machine the said holes are immersed in the mercury. The pump head 43 being eccentrically positioned relative to the mercury causes a pump action which creates a suction in the holes 51 and 52 in plate 46 and a pressure through the holes 53 and 54 in plate 47. Thus fluid is drawn from the cavity 56 on the left hand side of the pump head and discharged into the cavity on the right hand of said pump head, as viewed in Fig. 1.

The rotor 10 is constructed at its periphery with a number of circumferentially extending fins 57 which are adapted to dip into the mercury at the lowermost portion of the machine and to become spaced from the surface of the mercury at the uppermost portion of the machine to form a passageway 58 in the cavity 56 between said rotor and the surface of the mercury at the upper portion of the machine. This passageway is in communication with the discharge end of the pump means of the invention. The cavity 56 is also in communication with the passageway 22. For this purpose a conical socket 59 is formed in the end of the rotor 10 and the end of the bushing 37 is constructed conical as indicated at 61. These parts are spaced from one another to leave a passageway 62 which communicates with the passageway 58 and also with the passageway 22.

Mercury may be placed into the drum by means of a valve 64 which has a funnel 65 forming a part thereof. This valve communicates with the enlarged portion 39 of bore 50 of drum 31. Mercury may be removed from the drum 31 by means of a petcock 66 which is screwed into the said drum so as to communicate with the enlarged portion 39 thereof.

The rotor 10 is driven by any suitable means such as pulleys, gears, or other transmission, which may be attached to the shaft 11 exteriorly of the machine. Such construction being well known in the art has not been shown in the drawings. The drum 31 is driven in the following manner: Formed on the flange 32 is a spur gear 66. This gear meshes with the pinion 67 mounted on the shaft 68. Shaft 68 is journaled in a bearing 69 formed on the standard 14. The shaft 68, similar to the shaft 11, may be driven

by any suitable means, not shown in the drawings.

The method of operation of the invention is as follows: The desired quantity of mercury is first placed into the drum 31 through the funnel 65 and valve 64. This valve is then closed. The shaft 11 and the shaft 68 are next brought up to proper speed. This causes the mercury to be thrown outwardly by centrifugal force and to assume the form of a hollow cylinder, as indicated in Fig. 1. Rotation of the pump head 43 causes a suction on the left hand side of the said pump head and pressure on the right hand side thereof. The ore from which the gold is to be removed is crushed and mixed with water and the substance introduced into the machine through the pipe 25. The water and ore passes from this pipe through the passageways 26 and 21 into the left hand end of the cavity 56 within the mercury 55. The same is then drawn through the pump and discharged under pressure into the passageway 58. Here the particles of ore and gold are dragged around by the peripheral edges of the fins 57 and immersed into the mercury where amalgamation of the gold with the mercury occurs. As this process continues the residue is forced toward the right as viewed in Fig. 1, and finally discharged from the machine through the passageways 62, 22 and 28 leaving the machine through the pipe 29. During operation of the machine the threads 41 cause circulation of the mercury axially with respect to the machine so that uniform amalgamation occurs whereby more effective extraction of the gold can be secured. After the desired degree of amalgamation has been procured the machine is stopped and the drum 31 turned until the petcock 66 is at the lowermost portion of the same. This petcock and the valve 64 are then opened and the mercury drained out of the machine and into a suitable receptacle. The gold may thereafter be reclaimed from the mercury or by distillation or any other suitable manner.

The advantages of my invention are readily apparent. The machine is extremely small and compact. The mercury in the machine serves a two-fold purpose. In addition to extracting the gold it forms an element of the pump mechanism by means of which the ore is conducted through the machine. Due to the extended area of the edges of the fins which immerse the ore into the mercury, flake-like particles of ore which have a large area and small weight can be readily immersed in the mercury and amalgamated. My invention can be constructed at a nominal cost, and if desired can be made portable. The device is extremely simple in construction and will not readily get out of order.

Changes in the specific form of my invention, as herein disclosed, may be made within the scope of what is claimed without departing from the spirit of my invention.

Having described my invention, what I claim as new and desire to protect by Letters Patent is:

1. In combination, a revoluble drum for the reception of a quantity of mercury having a substantially horizontal axis, a rotor within the drum, said rotor being eccentrically disposed within said drum and dipping partly into the mercury on one side and being free from the mercury on the other side, means for rotating the rotor, means for feeding ore into the drum, said rotor serving to immerse the ore into the

mercury, and means for removing the residue from the drum.

2. In combination, a drum for the reception of a quantity of mercury, means for rotating the mercury to maintain the mercury within the drum in the form of a hollow cylinder disposed at the inner periphery of the drum, a rotor within the drum and situated eccentrically with reference to the cylinder, said rotor having a diameter and location such as to cause one portion thereof to dip into the mercury and the opposite portion to become spaced from the mercury to form a passageway therebetween, means for feeding ore into said passageway at one end, and means for removing the residue from said passageway at its other end.

3. In combination, a drum for the reception of a quantity of mercury, means for rotating the mercury to maintain the mercury within the drum in the form of a hollow cylinder disposed at the inner periphery of the drum, a rotor within the drum and situated eccentrically with reference to the cylinder, a plurality of fins extending circumferentially about said rotor, said rotor having a diameter such as to cause the fins at one portion thereof to dip into the mercury and at the opposite portion thereof to become spaced from the mercury to form a passageway therebetween, means for feeding ore into said passageway at one end, and means for removing the residue from the passageway at its other end.

4. In combination, a drum for the reception of a quantity of mercury, means for rotating the mercury to maintain the mercury within the drum in the form of a hollow cylinder disposed at the inner periphery of the drum, a rotor within the drum situated eccentrically with reference to the cylinder, said rotor having a diameter such as to cause the lowermost portion thereof to dip into the mercury and the upper portion thereof to become spaced from the mercury to form a passageway therebetween, means for feeding ore into said passageway at one end, and means for removing the residue from said passageway at its other end.

5. In combination, a drum for the reception of a quantity of mercury, means for rotating the mercury to maintain the mercury within the drum in the form of a hollow cylinder disposed at the inner periphery of the drum, a rotor within the drum and situated eccentrically with reference to the cylinder, a plurality of fins extending circumferentially about said rotor, said rotor having a diameter such as to cause the lower portions of the fins to dip into the mercury and the upper portions of the fins to become spaced from the mercury to form a passageway therebetween, means for feeding ore into said passageway at one end, and means for removing the residue from said passageway at its other end.

6. In combination, a drum for the reception of a quantity of mercury, means for rotating the mercury to maintain the mercury within the drum in the form of a hollow cylinder disposed at the inner periphery of the drum, threads formed upon the inner surface of the drum for moving the mercury axially along said drum, a rotor within the drum situated eccentrically with reference to the cylinder, said rotor having a diameter such as to cause one portion thereof to dip into the mercury and the opposite portion to become spaced from the mercury to form a passageway therebetween, means for feeding ore into said passageway at one end, and means for

removing the residue from said passageway at its other end.

7. In combination, a drum for the reception of a quantity of mercury, means for rotating the mercury to maintain the mercury within the drum in the form of a hollow cylinder disposed at the inner periphery of the drum, threads formed upon the inner surface of the drum for moving the mercury axially along said drum, a rotor within the drum situated eccentrically with reference to the annulus, a plurality of fins extending circumferentially about said rotor, said rotor having a diameter such as to cause the fins at one portion thereof to dip into the mercury and at the opposite portion thereof to become spaced from the mercury to form a passageway therebetween, means for feeding ore into said passageway at one end, and means for removing the residue from the passageway at its other end.

8. In combination, a drum for the reception of a quantity of mercury, a rotor within the drum situated eccentrically with reference thereto, a pump mechanism at one end of the rotor including a number of radially extending blades adapted to extend into the mercury and cause rotation of the mercury at such end of the drum, means for feeding ore to the pump mechanism, fins on said rotor, said fins dipping into the mercury along one portion of the same and being spaced from the mercury at another portion of the same to provide a passageway therebetween, said pump means discharging the ore into the passageway, said fins causing mixing of the ore with the mercury, and means for removing the residue from said passageway at the end thereof opposite the pump mechanism.

9. In combination, two spaced hollow tubular supports, bearings formed in said supports, a shaft rotatable in said bearings, said shaft forming annular passageways with respect to said supports, eccentric bushings mounted on said tubular supports, a drum rotatable on said bushings and having a quantity of mercury therein, means for rotating the mercury to maintain the mercury within the drum in the form of a hollow cylinder disposed at the inner periphery of the drum, a rotor within said drum carried by said shaft, said rotor dipping into the mercury, means for rotating the shaft, means for feeding ore into one of said annular passageways, and means for removing the residue from the other annular passageway.

10. In combination, two spaced hollow tubular supports, bearings formed in said supports, a shaft rotatable in said bearings, said shaft forming annular passageways with respect to said supports, eccentric bushings mounted on said tubular supports, a drum rotatable on said bushings and having a quantity of mercury therein, means for rotating the drum to maintain the mercury within the drum in the form of a hollow cylinder disposed at the inner periphery of the drum, a rotor within said drum carried by said shaft, a plurality of fins extending circumferentially about said drum and dipping into the mercury at one locality thereof, said fins being spaced from the mercury at another locality to form a passageway therebetween, one of said annular passageways communicating with said last named passageway at one end, and the other of said passageways communicating with said last passageway at its other end, means for feeding ore into one of said annular passageways, and

means for removing the residue within the drum from the other of said annular passageway.

11. In combination, two spaced hollow tubular supports, bearings formed in said supports, a shaft rotatable in said bearings, said shaft forming annular passageways with respect to said supports, eccentric bushings mounted on said tubular supports, a drum rotatable on said bushings and having a quantity of mercury therein, means for rotating the drum to maintain the mercury within the drum in the form of a hollow cylinder disposed at the inner periphery of the drum, a rotor within said drum carried by said shaft, a plurality of fins extending circumferentially about said drum and dipping into

the mercury at one locality thereof; said fins being spaced from the mercury at another locality to form a passageway therebetween, one of said annular passageways communicating with said last named passageway at one end, pump means on said rotor acting with the mercury in the drum to bring said other annular passageway into communication with the other end of said last named passageway, means for feeding ore 10 into the annular passageway communicating with said pump means, and means for removing the residue from said last named passageway through the other annular passageway.
